UNITED STATES PATENT OFFICE.

THERON BOARDMAN, OF BUFFALO, NEW YORK.

HARNESS.

SPECIFICATION forming part of Letters Patent No. 225,328, dated March 9, 1880.

Application filed October 1, 1879.

To all whom it may concern:

Be it known that I, THERON BOARDMAN, of the city of Buffalo, in the county of Erie and State of New York, have invented new and 5 useful Improvements in Harness, of which the following is a specification, reference being had to the accompanying drawings.

My invention relates to harness for draft-animals which are employed in drawing heavy 10 loads, such as canal-boats, street-cars, &c.

The object of my invention is to distribute the strain more evenly upon the shoulders and the breast of the draft-animal, and to render the harness readily removable from the draft- 15 animal.

My invention consists, to that end, in the combination, with the hame, of a combined hame-collar and breast-collar secured to the hame and connected with the trace by two 20 tugs, one of which is attached to the hame-staple and the other to the breast-collar, as will be hereinafter fully set forth.

In the accompanying drawings, Figure 1 is a side elevation of my improved harness applied to a horse. Fig. 2 is a front elevation of one-half of the harness. Fig. 3 is a horizontal section of the equalizer and bifurcated bearing connected thereto.

Like letters of reference designate similar 30 parts in the several figures.

A represents a hame, and B the combined hame - collar and breast - collar, made in one piece and secured to the inner side of the hame by rivets *c* or any other suitable means.

35 The collar B is composed of two halves, each secured to its respective hame, and provided at its upper and lower ends with suitable straps and buckles or other fastening devices, whereby the two parts are readily secured to-

40 gether at the front, when applied to the draft-animal, so as to form a complete collar.

D is the hame-tug, attached to the hame-staple *e* in the usual manner; and F is the breast-tug arranged near the lower end of the 45 collar B, so as to form a continuation of the breast-collar.

The two tugs D and F are connected with their rear ends, respectively, to the upper and lower ends of an equalizer, G. The latter 50 consists of a two-armed lever, which is pivoted between the jaws of a bifurcated bearing, H, secured to the forward end of the trace I.

The equalizer G is preferably provided with

several holes, *i*, in either of which the fulcrum-pin *k* may be placed. The latter is made in 55 the form of a thumb-screw or in any other suitable form, so as to be readily removable.

The strain of the trace I is distributed by the tugs D and F upon the hame and breast collars, and as the halves of the hame and 60 breast collars which lie on the same side of the draft-animal are made in one piece and secured to the respective part of the hame, the strain is evenly distributed upon the shoulders and breast of the animal, and excessive 65 pressure upon any one point and the galling resulting therefrom are entirely avoided.

By shifting the fulcrum-pin *k* the relative length of the two arms of the equalizer G can be altered, and the strain can be divided un- 70 equally between the tugs D and F, if it is desired to relieve either of them of a portion of the strain, when circumstances render this desirable.

Upon disconnecting the fastenings at the 75 front which hold the two halves of the harness together, the latter can be readily removed from the animal and as readily be applied to another animal. This is especially desirable when the harness is designed for use upon 80 animals which are employed in drawing street-cars and canal-boats, as these animals are frequently required to be changed without changing the harness.

I claim as my invention and desire to secure 85 by Letters Patent—

1. The combination, with the hame A, of the collar B, composed of a hame-collar and a breast-collar made in one piece and secured to the hame, and the tugs D and F connect- 90 ing the hame and collar with the trace, substantially as set forth.

2. The combination, with the hame A and the combined hame and breast collar B, of the tugs D and F, equalizer G, and trace I, sub- 95 stantially as set forth.

3. The combination, with the tugs D and F and trace I, of the equalizer G, provided with a series of fulcrum-holes, *i*, and a removable fulcrum-pin, *k*, substantially as and for the purpose set forth. 100

THERON BOARDMAN.
